UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-BOBBIN.

1,220,685.

Specification of Letters Patent. Patented Mar. 27, 1917.

Application filed August 2, 1915. Serial No. 43,088.

To all whom it may concern:

Be it known that I, EPPA H. RYON, a citizen of the United States, residing at Waltham, in the county of Middlesex and State 5 of Massachusetts, have invented a new and useful Weft-Bobbin, of which the following is a specification.

This invention relates to a weft bobbin particularly designed for used in conjunction 10 with the weft detecting mechanism or feeler of special construction which constitutes the subject matter of my companion application, Serial No. 43,089, filed on even date herewith.

15 My present invention consists in the provision of a plurality of radial holes extending through the cylindrical side walls of the barrel portion of a weft bobbin, these holes being so disposed that they will 20 operate with a series of detecting members to cause the renewal of the weft supply whenever the weft upon the bobbin in the active shuttle becomes so far exhausted as to uncover said radial holes.

25 My invention further consists in certain arrangements and combinations of parts which will be hereinafter described and more particularly pointed out in the appended claim.

30 A preferred form of my invention is shown in the drawings, in which—

Figure 1 is a plan view of a bobbin embodying my invention;

Fig. 2 shows the bobbin in position within 35 a shuttle and coöperating with a portion of the detecting mechanism, and

Fig. 3 is a development of the cylindrical barrel portion of the bobbin.

Referring to the drawings it will be seen 40 that the weft bobbin 10 is of a common type, having a butt 11 provided with rings 12 adapted for engagement by a shuttle spring 13, by which the bobbin is positioned and held within a shuttle 14 of usual construction. The shuttle 14 is provided with a slot 45 15 through which the detecting mechanism operates.

The bobbin 10 is provided with the usual 50 hollow cylindrical barrel portion 16 adjacent the butt 11, this being a familiar feature in weft bobbins intended for use in so-called "feeler" looms.

The essential novelty in my improved weft 55 bobbin consists in the provision of a plurality of radial holes 17 extending through

the cylindrical side walls of the barrel portion 16 and communicating with the hollow interior portion of the bobbin. The relative arrangement of the holes 17 in the barrel 16 is clearly shown in Fig. 3 in which it 60 appears that the holes are arranged in three circumferential series a , a' and a'' extending entirely around the bobbin, and that they are also arranged in a plurality of parallel spiral curves b , b' , b'' and b''' . It also appears that the holes 17 are of such diameter and are so spaced and arranged relatively to each other that it is impossible to draw a line c extending axially along the surface of the barrel 16 without crossing one or more 70 of the holes 17.

In the preferred form of my invention, the holes 17 are circular and are approximately one-quarter of an inch in diameter, and each hole is spaced from all adjacent 75 holes by approximately the same distance. With this arrangement, I am able to cut the holes entirely through the walls of the bobbin without materially weakening the bobbin.

The weft bobbin 10 is intended for use in coöperation with a weft detector or feeler of special construction, said feeler including a detector slide 18 within which a plurality of detecting members or rods 19 are mounted 80 for longitudinal movement. The entire series of rods 19 is positioned for engagement by the bobbin 10 as it approaches its forward limit of travel and so long as the holes 16 are covered by the weft or filling 90 the detecting members 19 are all forced forwardly by the bobbin to their inoperative position.

When the holes 17 are uncovered by the substantial exhaustion of the weft, one or 95 more of the rods 19 will enter certain of the holes 17 and will thus remain in their outer or rear position during the forward movement of the bobbin. By thus remaining in their outer or normal positions, they render 100 the weft replenishing mechanism operative. The details of this mechanism form no part of the invention embodied in this application and for a full description thereof, reference is made to the companion applica- 105 tion above identified.

It should be noted that the weft bobbin herein described possesses important advantages both in construction and in utility. The holes 17 are of such size and are so 110

distributed that they do not unduly impair the strength of the bobbin. Furthermore, by the provision of several series of holes extending entirely around the bobbin and so spaced that one or more of said holes must always be located in the path of the detecting members, I avoid the necessity of placing the bobbin within the shuttle in any particular predetermined position.

10 The bobbins 10 are of usual construction and the ordinary feeler bobbins previously in use can be readily adapted for use with my improved detecting mechanism by providing them with holes 17 properly spaced 15 and positioned in the barrel portion thereof.

Having thus described my invention, it will be evident that changes and modifications can be made therein by those skilled in the art without departing from the 20 spirit and scope thereof as set forth in the

claim. Accordingly I do not wish to be otherwise limited to the details herein disclosed, but what I do claim is:—

A weft bobbin having a butt, and a hollow portion adjacent said butt, and also having a plurality of circular holes extending entirely through the wall of said portion to the hollow interior thereof, holes longitudinally adjacent being angularly disposed relatively to each other and each hole being approximately one-quarter of an inch in diameter and being separated from all adjacent holes by distances not substantially less than one-quarter of an inch, whereby the strength of said bobbin is not 30 materially decreased. 35

In testimony whereof I have hereunto set my hand.

EPPA H. RYON.
